UNITED STATES PATENT OFFICE.

PERCY E. MATTHES, OF PHILADELPHIA, PENNSYLVANIA.

DESIGN FOR A BICYCLE-ALARM.

SPECIFICATION forming part of Design No. 25,880, dated August 4, 1896.

Application filed February 26, 1896. Serial No. 580,920. Term of patent 14 years.

To all whom it may concern:

Be it known that I, PERCY E. MATTHES, a citizen of the United States, residing at Philadelphia, in the county of Philadelphia and 5 State of Pennsylvania, have invented and produced a new and original Design for Bicycle-Alarms; and I do declare the following to be a full, clear, and exact description of the same, reference being had to the accompanying drawings, forming a part thereof.

My device consists in the configuration given to the alarm, substantially as herein-after described.

Figure 1 is a side view of said alarm, and 15 Fig. 2 is a top view.

Similar letters of reference indicate like parts.

The inner portion of the alarm A is ring-shaped, having the interior 1 thereof flat and 20 the exterior 2 rounded. At substantially equal distances apart appear bell-shaped por-

tions B, extending radially from the said inner portions, the width of the bell-shaped portions being much greater than that of the ring-shaped portions. The bell-shaped portions appear to stand at a little distance from the ring-shaped portion, and with the narrow parts of the former nearest the ring-shaped portion. Between each of the bell-shaped portions and the rounded portion of the ring-shaped portion appear the parts C of greater length than width.

I claim as my invention—

The design for a bicycle-alarm substantially as shown and described. 35

In testimony whereof I affix my signature in presence of two witnesses.

PERCY E. MATTHES.
